Attorney.

UNITED STATES PATENT OFFICE

EDWARD L. BENEDICT, OF PITTSBURGH, PENNSYLVANIA, ASSIGNOR TO PITTSBURGH STEEL COMPANY, OF PITTSBURGH, PENNSYLVANIA, A CORPORATION OF PENNSYLVANIA

REINFORCED PLASTIC STRUCTURE

Application filed June 30, 1928. Serial No. 289,524.

My invention relates to reenforced structures of concrete, plaster, and the like, such as walls, partitions, slabs, etc.

One object of my invention is to provide a structure of concrete, plaster or the like, wherein reenforcement is effectively embedded and wherein no special or temporary forms are required in the making of the body.

Still another object of my invention is to simplify and improve generally bodies formed of plastic material and the method of making the same.

One manner in which my invention may be practiced is shown in the accompanying drawings, wherein Figure 1 is a fragmentary front elevational view of a wall or slab constructed according to my invention; Fig. 2 is an edge elevational view of the structure of Fig. 1, at one stage in the process of making the same, and Fig. 3 is a view similar to Fig. 2, but showing the process of manufacture continued to the stage at which a slab or block is formed.

In practicing my invention according to the manner shown in the drawings, I provide main reenforcing members consisting of bars or wires 4 and 5 that may be welded or otherwise suitably connected at their points of intersection to form a mesh-like body. A backing sheet 6 of wire cloth or the like is attached to the mesh formed by the bars 4 and 5, by means of thread-like wires 7 which are disposed mainly to the rear of the sheet 6, as shown more clearly in Fig. 2, and at intervals 35 have bends 8 formed therein that extend to the front of the sheet 6 and around certain of the strand wires or rods 4, somewhat after the manner shown in my Patent No. 1,597,507, issued August 24, 1926.

Various other means may be provided for connecting the wire cloth to the mesh structure, such for instance as those shown in my Patent No. 1,502,012, issued July 22, 1924.

The wire cloth 6 serves as a backing sheet to support a plaster or cement body 9 that may be applied to the front of the sheet by means of a trowel, a cement gun, or in any other suitable manner. If the mesh structure be placed against studding, and it is desired to face only the outer side, as in the case of

walls or partitions, the completed structure will have, when viewed in section, the appearance shown in Fig. 2, the plaster facing 9 being of course applied to any desired thickness and completely surrounding the bars 4 and 5. It will also be seen that an interlocking effect can be had between the plaster and the wire cloth or backing sheet 6, by reason of the fact that small portions of the plaster may be forced through such sheet, as indicated at 10. The wire cloth therefore not only serves as a backing or form sheet, but also assists in reenforcing and permanently supporting the plaster body since the openings through the backing sheet are so close together that the portions of plaster which are forced therethrough will unite at the rear side of the sheet to effect substantially complete imbedment thereof as shown in Fig. 2, where the protrusions 10 are shown as united together for a distance substantially equal to the thickness of the thread wire 7. The portions 10 of the plaster will of course be compressed when being forced through the backing sheet and relief of such pressure at the rear side of the backing sheet will effect the slight expansion thereof, necessary to cause them to unite at the rear sides of the wires forming the backing sheet 6.

If it is desired to form a slab or to finish both sides of the structure by a plaster facing, I apply a facing 11 (Fig. 3) to the rear side of the structure of Fig. 2, to any desired depth. An effective interlocking of the rear facing 11 with the main body of the structure is secured by reason of the protrusions 10 that extend to the rear of the wire cloth 6.

It will be understood that the backing sheet 6 need not be of wire cloth but may be of various other material such as fiber, paper, or the like, having perforations through which plaster may be forced when facing one side of the sheet. It will also be understood that various forms of reenforcement other than the bars 4 and 5 may be utilized.

When the backing sheet 6 is supported in spaced relation to the mesh bars 4-5, as shown in the drawings, the said bars are thereby permitted to be completely surrounded by the main body of plastic material so

that they are completely imbedded and more effectively reenforce the body than if the backing sheet were disposed directly against the bars.

5 While I hereinafter claim the structure as a plaster body, it will be understood that the term "plaster" is used in a broad sense, to include concrete, various stucco materials, etc.

I claim as my invention:—

10 A plaster body composed of a reenforcing mesh, a loosely-woven wire cloth backing sheet disposed rearwardly of the mesh, tie members supporting the cloth in completely spaced relation to the mesh, and plaster material completely imbedding the mesh and having protrusions extending through the wire cloth and partially imbedding the same, the strands of the cloth being spaced apart such distance as to permit the said protruding portions of the material to be forced through the cloth.

In testimony whereof I, the said EDWARD L. BENEDICT, have hereunto set my hand.
EDWARD L. BENEDICT.
